ELECTRIC RELAY SYSTEM

Carl P. Clare, Arlington Heights, Ill., assignor to
C. P. Clare and Co., Chicago, Ill., a corporation
of Illinois

Application January 4, 1941, Serial No. 373,173

9 Claims. (Cl. 177—353)

My invention relates broadly to remote control systems and more particularly to an electric relay system for use in remote control systems.

One of the objects of my invention is to provide an electric relay system for operation in a remote control system by which various circuit permutations and combinations may be effected and in addition a repeating warning signal may be controlled by the relay system.

Another object of my invention is to provide an electric relay system including a solenoid and moving armature system adapted to control a multiplicity of sets of spring contacts, one set of which is arranged in the control circuit to the solenoid winding and in which the armature is characterized by such inertia that combined mechanical and electrical forces are employed to effect repeated make and break operations of the sets of spring contacts for effecting the transmission of a warning signal of predetermined characteristic.

Still another object of my invention is to provide a construction of electric relay employing a solenoid winding and a weighted armature having means for imparting make and break movement to a multiplicity of sets of spring contact members in a spring pile-up where one of the sets of contact members is arranged in series with the control circuit to the solenoid winding and the inertia of the weighted armature employed for limiting the movement of the armature with respect to the spring pile-up to repeated short strokes for impressing a warning signal of predetermined characteristics from a source to a control circuit through other sets of the spring contact members.

A further object of my invention is to provide an electric relay system including a core structure, an operating winding, a movable armature controlled thereby and a spring pile-up including a multiplicity of sets of contact members, one set of which is disposed in series with the solenoid winding wherein electrical and mechanical forces are introduced upon excitation of the solenoid winding to cause rapid repeat movements of the armature and corresponding rapid make and break operations of the sets of contact members, and certain of which control the application of a power source of predetermined characteristic to a control circuit.

A still further object of my invention resides in the method of controlling the operation of an electric relay system which consists in introducing an opposing field into the field of the winding of the relay means for controlling the elec-

trical time period of operation of the armature and controlling the inertia of the armature for mechanically controlling the movement thereof whereby a spring pile-up system may be operated by the movement of the armature at a predetermined rate for correspondingly controlling an electrical system through the make and break operations thereof.

Another object of my invention is to provide an electric relay system including a controlling winding, a movable armature and a spring pile-up assembly in which the operate time is both electrically and mechanically controlled so that a series of short strokes may be imparted to the spring pile-up assembly upon application of a continuous current to the relay winding for controlling through the spring pile-up assembly the repeated application of the control current to the controlled circuit.

Still another object of my invention is to provide an electric relay system including an operating winding, a movable armature and a spring pile-up assembly having means for normally exerting a restoring force on the movable armature, and including means for electrically controlling the operate time of the winding and mechanically controlling the inertia of the movable armature so that the flux cycle in the magnetic parts may be regulated to control at comparatively high speed the operation of the spring pile-up assembly upon application of a continuous current to the relay winding for controlling through the pile-up assembly the application of current of predetermined characteristic to a control circuit.

Other and further objects of my invention reside in an arrangement of electric relay system having means for controlling the operate and release time of the magnetic system of the relay as set forth more fully in the specification hereinafter following by reference to the accompanying drawings, in which:

Figure 1 is a schematic wiring diagram showing one application of the electric relay system of my invention to a remote control system of a radio transmitter whereby a warning signal may be transmitted from the radio transmitter to signify the commencement of a broadcast; Fig. 2 shows a characteristic curve for an electric relay system in which the electrical operating time of the relay system is regulated in accordance with the principles of my invention; Fig. 3 shows a characteristic curve in which both the electrical and mechanical characteristics of the relay system are controlled for securing the repeat signal

operation required as a warning signal in the remote control system illustrated in Fig. 1; Fig. 4 is a side elevational view showing the construction of the electric relay employed in the electric relay system of my invention, parts being broken away and illustrated in section for more clearly illustrating my invention, the view being shown with the armature in normal position with a normal restoring force exerted thereon by the spring pile-up; Fig. 5 is a side elevational view of the electric relay system illustrated in Fig. 4 showing the armature moved to operate position and illustrating the displacement of the contact members under control of the movement of the armature; Fig. 6 is a top plan view of the electric relay illustrated in Figs. 4 and 5; Fig. 7 is a vertical transverse sectional view taken on line 7—7 of Fig. 4; Fig. 8 is a vertical transverse sectional view taken substantially on line 8—8 of Fig. 4; Fig. 9 is a perspective view illustrating the weighted armature, the lever arm associated therewith and the bearing for pivotally mounting the armature; and Fig. 10 is a schematic view showing the electrical self-interrupting circuit arrangement of the electric relay system and illustrating the means for both electrically and mechanically controlling the operating time of the relay for correspondingly controlling the operation of the spring contacts of the spring pile-up.

My invention provides a method of remote control for a radio broadcast transmitter or other signalling system for transmitting a warning signal in advance of a broadcast. The system of my invention is particularly applicable in aircraft traffic control and navigation systems in which an operator in a remote position with respect to a transmitting ground station is required to notify aircraft that a broadcast is about to commence. The operator in the remote control station may dial a particular digit on the remote control mechanism at the control station and then hold down the signalling key and in accordance with the system of my invention effect the transmission of warning signals at a rate of approximately eight per second on any selected audio tone frequency such as 1,020 cycles. The warning signals at 1,020 cycles are transmitted so long as the control operator holds the control key closed, thereby advising the pilots of aircraft that a broadcast is about to commence. This method of transmission has proven highly effective in the transmission of weather, emergency, traffic and other information to aircraft in a particular area. However, my invention is not limited to this particular application and is applicable to signalling systems generally in which a calling signal of predetermined characteristic is to be transmitted in advance of the signalling operation. My invention also has application to the transmission of signals of particular tones for controlling of start-stop functions for the motor circuits of facsimile and printing telegraph systems and for the starting and stopping of the auxiliary control circuits of television equipment by remote control.

Referring to the drawings in detail, I have illustrated a remote control system of general application in which in Fig. 1 the equipment at the remote control station is designated generally at 11 while the equipment at the transmitting station is indicated generally by reference character 12 with the line system 13 interconnecting the stations. An alternating current supply circuit has been illustrated generally at 14 coupled

through transformer 15 to the contacts of the control key 18 for controlling connections to the line system 13. The control key 18 is indicated generally as having a dial position 19 and a ringing position 20. The dial switch control device at the remote control station is indicated at 16. The signalling circuit is indicated at 17 having leads L1 and L2 normally connected through key 18 to the line 13. The operator at the remote control station by moving key 18 to the dial position 19 and operating the dial 16 opens and closes the circuit over line 13 for transmitting impulses to the controlled station. At the controlled station relay A—4196 follows these impulses and through its back contact 1 causes the motor magnet 10 through intermediate relay B—4196 to actuate the stepping switch 21—22 the specific number of steps corresponding to the impulses transmitted from the dial through any suitable range such as 1', 2'—30'. Relay B—4196 and a cut-out relay D—4196 are both of a slow release type. The intermediate relay B—4196 due to its slow release action remains operated after its circuit is first closed, thus holding its contacts 25 2—3 closed. After the last impulse from the dial, relay D—4196, which operated on the first impulse from relay A—4196 and remains operated during the series of impulses transmitted from the dial, restores and closes a circuit from 30 positive on contact 2 of relay A—4196 to the primary relay associated with the last stepping relay step. Relay A—4196 remains energized so long as key 18 remains in dial position after 35 the series of impulses has been transmitted, in order to maintain the selected primary relay energized.

This primary relay operates to close a circuit to the desired control which is required. This control may be the closing of certain amplifier circuits or other desired switching operations. In the particular system illustrated, I have shown the broadcast transmitter as comprising a modulation system 29, an oscillator 31, a power amplifier 32 and an antenna system 33. A modulation control circuit 28 extends to the modulator 29 and a local microphone 34 is provided in this circuit for any local control which may be required. An audio frequency transformer 27 has its secondary winding connected to modulation 45 circuit 28 and its primary winding connected to the leaf springs 25 and 26 of the spring pile-up 24 of the auxiliary relay 39. The contact springs 25 and 26 move to either of two positions. In the upper position, contact springs 25 and 26 connect with contacts 35 and 36 which connect to the contacts 4 and 6 of the contact assembly 23 of relay B—4196. In the opposite position, leaf springs 25 and 26 connect respectively with contacts 37 and 38 leading to the tone frequency source under control of the relay system 42 of my invention. The relay 42 comprises the magnetic core 44, the operating winding 43, the slow operate slug 45 for electrically controlling the operating time of the relay and the armature 46 pivoted at 47. The armature 46 has an operating lever arm 49 integral therewith which controls the operation of the spring pile-up shown at 50. The armature 46 has the inertia device 48 attached thereto for mechanically controlling the operating time of the relay. The spring pile-up 50 includes leaf springs 51, 52, 53, 54, 55 and 56. The leaf springs 51—52 carry contacts 51a and 52a which are electrically connected in series 70 with the control winding 43 and with the power

source through contact spring 48 and coating contact 41 of auxiliary relay 39. The relay 42 is thus self-interrupting through the cooperation of contacts 51a and 52a in the current path to the relay winding 43 at a rate of time depending upon the coaction of the inertia of armature 46 due to the added mass 48 and the influence of the eddy current field produced by slug 45 upon the normal field of winding 43.

A suitable source of alternating current having a tone frequency, for example, of 1020 cycles is connected at 57 to primary winding 58 of transformer 59, whose secondary winding 60 is connected to leaf springs 54 and 56 of spring pile-up 50. The movable contact springs 52, 53 and 55 are interconnected through bushings of insulation material indicated at 61 and 62 so that movement of lever arm 49 moves leaf spring 52 to open contacts 51a and 52a while leaf springs 53 and 55 move to positions in which contacts 53a and 55a establish connection with contacts 54a and 56a, respectively, thus closing the circuit from secondary winding 60 of transformer 59 to the contacts 37 and 38 of spring pile-up 24 of auxiliary relay 39. I have schematically illustrated the primary relays of the remote control system at E—4196 and F—4196 and the secondary relays at G—4196. I have schematically shown the several contacts and leaf springs for the several relays and control apparatus at 1, 2, 3, 4, 5, 6, 7, 8 and 9 with polarities indicated to aid in tracing the circuits of the control system.

In the instant case assume that it is desired to broadcast a certain message. The operator moves key 18 to dial position 19 and dials the digit 3 which causes the stepping switch 21—22 to step to its third contacts, and relay A—4196 to remain energized afterward. Relay D—4196 on restoring after the third impulse closes a circuit to primary relay 3. Primary relay 3 closes a circuit to the auxiliary relay 39 which transfers the circuit from contacts 23 leading to the modulation channel through the primary of the broadcast transformer 27 to contacts 54 and 56 on the weighted armature relay 42 of my invention. The circuit to the winding 43 of the weighted armature relay 42 is also closed by the auxiliary relay 39 through spring 40 and contact 41 and as previously described, the weighted armature relay 42 operates approximately eight times per second to cause a warning 1020 cycle tone to be placed on the modulation circuit 28 of the broadcast station. This interrupted tone is held on the modulation circuit of the broadcast station as long as the operator at the distant control station holds his key 18 operated at dial position. After this tone has been held on the desired length of time the operator restores his key 18 to neutral position and the stepping switch 21—22 restores itself to normal. The control operator by using key 18 and dial 16 as before, then dials the broadcast number and the stepping switch 21—22 functions to operate the primary and secondary relays to effect whatever functions they control, with leaf springs 25—26 of spring pile-up 24 contacting the contacts 35 and 36 as shown in Fig. 1, after which key 18 is restored and the broadcast takes place.

In Figs. 4—9 I have shown more particularly the mechanical construction of the relay system of my invention. The relay is shown mounted upon any suitable base 63 by means of a bracket 64 secured to the base by suitable means 65. The core structure 44 is provided with spool head 66 formed from insulation material and recessed

at opposite sides thereof for the passage of terminals 67. Winding insulators 68 and 69, blanked from hard rubber sheet, free of acid and alkali, form end members between which the turns of the operating winding 43 are wound over the tubular base of insulation material such as heavy empire cloth 70. The turns of winding 43 are protected by a wrapping of insulation material indicated at 71. The slow operating control slug is indicated at 45 abutting against the disc-like winding insulation 69. The slug 45 is generally formed from copper which is toroidal in shape and forms a solid short circuiting ring immediately in the flux of the magnetic field of winding 43 and introduces predetermined eddy current losses controlling the electrical time period of operation of the solenoid. The copper slug 45 is off-set sufficiently from the end of the core 44 to allow the magnetic lines from core 44 to readily thread the magnetic path through the movable armature 46, the heavy duty bearing member 72 and the magnetic frame 73 which is integral with the magnetic heelpiece 74 which is secured to the end of the magnetic core 44; to facilitate formation of the heelpiece 74 integral with the frame 73, a portion of frame 73 is removed adjacent the end of the frame as indicated at 73a. The heelpiece 74 is secured by suitable screws 75 to the upper portion of the bracket 64. The magnetic path is limited to the core 44, armature 46, bearing member 72, frame 73 and heelpiece 74 by reason of the insulation member 76 disposed between the heelpiece 74 and the bracket 64 and by the bushings of insulation material indicated at 77 which center the securing means 75 away from bracket 64. The apertures in bracket 64 for the passage of terminals 67 are of such size as will permit the passage of terminals 67 without contact with bracket 64.

40 The armature 46 is centrally apertured at 78 for the passage of screw 79 which enters the end of weight 48, securing weight 48 to the movable armature and thereby introducing predetermined inertia in the movement of the armature. Weight 48 is in the shape of an extended rod forming a lever arm which controls the angular movement of armature 46 about the pivot 41. The pivot 41 comprises a rod member 80 which passes through the lugs 46a on armature 46 and is journaled in the heavy duty sleeve bearings 81 which fit within the cylindrical recesses 72a in bearing member 72. These heavy duty bearings constitute self-lubricating means for journaling the armature which because of the rapid and repeating operation of the armature in this particular class of relay requires a much more substantial bearing than is customary. The bearing member 72 is recessed at 72b and is slotted at 72c, permitting the passage of screw 82 therethrough and through yieldable washer 83. Washer 83 has a lug 83a thereon which extends into a centering aperture 73b retaining the washer 83 in a fixed position with respect to screw 82. This arrangement permits adjustment of the position of the pivot 41 of the armature and control of the spacial relation of the armature 46 with respect to the end of the magnetic core 44 by loosening screw 82 and allowing bearing 72 to be moved forward or backward with slots 72c embracing opposite sides of screw 82 while washer 83 is maintained in a fixed position by engagement of lug 83a in aperture 73b of frame 73.

45 The spring pile-assembly 50 is constituted by the leaf spring members and associated contacts

as heretofore explained where the leaf spring members are secured in stacked arrangement by means of screws 84 which pass through top plate 85 and the insulation and spacer plates indicated at 86 assembled on opposite sides of leaf springs 51, 52, 53, 54, 55 and 56 as shown. The screws 84 also pass through the plate member 87 which is provided with a stop arm 88 thereon which projects into the path of the lever arm 49 forming an abutment stop for lever arm 49 and thus limiting the normal unoperated position of armature 46 as shown in Fig. 4. The end of lever arm 49 has an upstanding pin 89 thereon forming a seat for an insulated button 90 which serves as the engagement means for the end of the lever arm with leaf spring 52. As indicated in Fig. 4 the insulated button 90 normally rests against leaf spring 52, the contacts 51a and 52a being closed while the contacts in the remaining portions of the spring pile-up assembly are open as represented in Fig. 4. However, in the energized conditions of the winding 43, armature 46 moves to the position shown in Fig. 5 opening contacts 51a and 52a and closing the circuits between the contacts carried by the set of leaf springs constituted by 53 and 54 and also the set of contacts constituted by the leaf springs 55 and 56 by reason of the coupled relation of the leaf springs through bushings 61 and 62 as shown in Figs. 4, 5 and 8. It will be seen in referring particularly to Fig. 8 that insulated bushing 61 is firmly riveted to leaf spring 53 while the somewhat longer bushing 62 is firmly riveted to leaf spring 55. Accordingly, movement imparted through insulated button 90 to leaf spring 52 is transferred through couplings 61 and 62 to leaf springs 53 and 55. Thus the self-interrupting circuit to the winding 43 is functioned at the same time that the control circuit contacts in the spring pile-up are opened and closed.

I have found the relay structure of my invention very practical and successful in operation. The mass added by weight 48 provides the movable armature system with that amount of mechanical inertia which will coact with the electrical influence introduced by slug 45 to enable operating winding 43 while energized from a continuously applied source to cause the controlled circuit connected through sets of contact springs 53, 54, 55 and 56 to alternately connect and disconnect a source of control potential to the circuit to be controlled. The rate at which this control is applied is readily controllable by changing the character of slug 45 and the effective mass 48, schematically illustrated in Fig. 10.

Figs. 2 and 3 illustrate the effect of the slug 45 and the weight 48 on the movable armature. In Fig. 2 the curves illustrate the manner in which the flux density increases and decreases in the magnetic system according to time where the flux builds up during the make period of contacts 51a and 52a and decreases to a condition where it commences to increase again before the flux cycle through the magnetic parts has been completed. The influence of slug 45 in the example illustrated is such that the flux cycle increases through a time period represented by a unit of time while the decrease in flux takes place over a fourth of the increase time. The self-interruption effected by the breaking of the circuit through winding 43 by contacts 51a and 52a produces a repetition of alternate increases and decreases of the flux cycle as illustrated. In order to increase the rate of make and break of the spring pile-up system the mass 48 is added to

5 armature 46 with the result shown in Fig. 3. The time period for initial build-up of the magnetic flux is now one unit of time compared to a tenth of the time for decrease of flux. The flux cycle is not completed but repeats in a series of substantially saw-tooth curves as indicated until the controlling current is removed. During this period the spring pile-up assembly is being functioned through a series of rapid repeating strokes and impresses the characteristic tone frequency from source 57 upon the load circuit or modulation circuit of the radio transmitter illustrated in Fig. 1. By proportioning the mass of the movable armature system and the arrangement of slug 45 in the field of winding 43 a rate of make and break of eight times per second or other rate may be obtained.

I realize that various changes may be made in the relay arrangement and while I have described my invention in certain preferred embodiments, I desire that it be understood that modifications may be made and I intend no limitation upon my invention other than may be imposed by the scope of the appended claims.

What I claim as new and desire to secure by Letters Patent of the United States is as follows:

1. An electrical relay system comprising in combination with a line circuit, controlling means including a dial switch associated with said line circuit, a signalling system, a self-commutating relay having a winding, a movable armature and a spring pile-up assembly, an audio frequency source, connections from said source and said signalling system to a portion of said spring pile-up assembly for impressing energy from said source upon said signalling system, means associated with said relay for timing the periodicity of application of said source to said signalling system, relay means responsive to the operation of said dial switch for establishing a circuit between said relay winding and said line circuit, and means independent of said dial switch for maintaining said line circuit closed over a selected time period for effecting successive repeat operations of said self commutating relay.

2. An electrical relay system comprising in combination with a line circuit, controlling means including a dial switch associated with said line circuit, a signalling system, a self-commutating relay having a winding, a movable armature and a spring pile-up assembly, an audio frequency source, connections from said source and said signalling system to a portion of said spring pile-up assembly for impressing energy from said source upon said signalling system, means mechanically associated with said movable armature for timing the periodicity of application of said source to said signalling system, relay means responsive to the operation of said dial switch for establishing a circuit between said relay winding and said line circuit, and means independent of said dial switch for maintaining said line circuit closed over a selected time period for effecting successive repeat operations of said self commutating relay.

3. An electrical relay system comprising in combination with a line circuit, controlling means including a dial switch associated with said line circuit, a signalling system, a self-commutating relay having a winding, a movable armature and a spring pile-up assembly, an audio frequency source, connections from said source and said signalling system to a portion of said spring pile-up assembly for impressing energy from

said source upon said signalling system, means magnetically associated with said winding for timing the periodicity of application of said source to said signalling system, relay means responsive to the operation of said dial switch for establishing a circuit between said relay winding and said line circuit, and means independent of said dial switch for maintaining said line circuit closed over a selected time period for effecting successive repeat operations of said self commutating relay.

4. An electrical relay system comprising in combination with a line circuit, controlling means including a dial switch associated with said line circuit, a signalling system, a self-commutating relay having a winding, a movable armature and a spring pile-up assembly, an audio frequency source, connections from said source and said signalling system to a portion of said spring pile-up assembly for impressing energy from said source upon said signalling system, means mechanically associated with said movable armature and cooperative means magnetically associated with said winding for timing the periodicity of application of said source to said signalling system, relay means responsive to the operation of said dial switch for establishing a circuit between said relay winding and said line circuit, and means independent of said dial switch for maintaining said line circuit closed over a selected time period for effecting successive repeat operations of said self commutating relay.

5. An electric relay system comprising in combination, a controlling circuit, a relay having a magnetic core structure, a movable armature, a winding controlled by said controlling circuit, means for determining the inertia of said armature in proportion to the magnetization of said core structure for inducing a characteristic movement in said armature, a spring pile-up assembly including a multiplicity of sets of spring contact members, one set of said members being electrically connected in series with said winding and said controlling circuit, means on said armature for controlling the making and breaking of each of the sets of spring contact members in accordance with the characteristic movement of said armature and the operation of said sets of contact members, a source of control potential of predetermined characteristics, a load circuit, connections from said source of control potential and said load circuit to said other sets of spring contact members for impressing said control potential upon said load circuit at a rate determined by the opening and closing of said first mentioned set of spring contact members, and means located at a control position in said controlling circuit for selectively closing the circuit through said winding for effecting recycling of said relay over a selected time period.

6. An electric relay system comprising in combination a controlling circuit, a relay having a magnetic core structure, a movable armature, a winding controlled by said controlling circuit, a spring pile-up assembly including a multiplicity of sets of spring contact members, one set of said members being electrically connected in series with said winding and said controlling circuit, means associated with said movable armature for regulating the inertia thereof and inducing a characteristic movement in said armature, means extending from said armature for effecting the making and breaking of each of the sets of spring contact members in accordance with the characteristic movement of the arma-

ture, a source of control potential of predetermined characteristics, a load circuit, connections from said source of control potential and said load circuit to said other sets of spring contact members for impressing said control potential upon said load circuit at a rate determined by the opening and closing of said first mentioned set of spring contact members, and means located at a control position in said controlling circuit for selectively closing the circuit through said winding for effecting recycling of said relay over a selected time period.

7. An electric relay system comprising in combination, a controlling circuit, a relay having a magnetic core structure, a movable armature, a winding controlled by said controlling circuit, a spring pile-up assembly including a multiplicity of sets of spring contact members, one set of said members being electrically connected in series with said winding and said controlling circuit, means disposed in the field of the magnetic flux of said winding for controlling the instantaneous net flux produced by the magnetic field of said winding and the corresponding influence thereof to induce a characteristic movement in said armature, means extending from said armature for effecting the making and breaking of each of the sets of spring contact members in accordance with the characteristic movement of said armature, a source of control potential of predetermined characteristics, a load circuit, connections from said source of control potential and said load circuit to said other sets of spring contact members for impressing said control potential upon said load circuit at a rate determined by the opening and closing of said first mentioned set of spring contact members, and means located at a control position in said controlling circuit for selectively closing the circuit through said winding for effecting recycling of said relay over a selected time period.

8. An electric relay system comprising in combination, a controlling circuit, a relay having a magnetic core structure, a movable armature, a winding controlled by said controlling circuit, a spring pile-up assembly including a multiplicity of sets of spring contact members, one set of said members being electrically connected in series with said winding and said controlling circuit, means disposed in the field of said winding for controlling the instantaneous net value of the magnetic flux in said winding, means associated with said movable armature for regulating the inertia thereof in proportion to said magnetic flux for inducing a characteristic movement of said armature under control of said winding, means extending from said armature for functioning said spring pile-up assembly for controlling the making and breaking of each of the sets of spring contact members, a source of control potential of predetermined characteristics, a load circuit, connections from said source of control potential and said load circuit to said other sets of spring contact members for impressing said control potential upon said load circuit at a rate determined by the opening and closing of said first mentioned set of spring contact members, and means located at a control position in said controlling circuit for selectively closing the circuit through said winding for effecting recycling of said relay over a selected time period.

9. An electrical relay system comprising in combination with a line circuit, controlling means associated with said line circuit, a signalling sys-

tem, a self-commutating relay having a winding controlled by said controlling means, a movable armature and a spring pile-up assembly, an audio frequency source, connections from said source and said signalling system to a portion of said spring pile-up assembly for impressing energy from said source upon said signalling system, a rod member fastened to said movable armature and extending therefrom and constituting a weighted lever arm for determining 10

the inertia of said armature in proportion to the magnetization of said relay for inducing a characteristic periodic movement of said armature and timing the periodicity of application of said source to said signalling system, and means located in a control position in said line circuit for selectively closing said line circuit through said winding for effecting recycling of said relay over a selected time period.

CARL P. CLARE.
